US0D1077046S

(12) **United States Design Patent** (10) **Patent No.:** **US D1,077,046 S**
Van Brakel (45) **Date of Patent:** **** May 27, 2025**

(54) **HANDLE FOR NANOIMPRINTING MACHINE**

(71) Applicant: **KONINKLIJKE PHILIPS N.V.**, Eindhoven (NL)

(72) Inventor: **Remco Van Brakel**, Eindhoven (NL)

(73) Assignee: **KONINKLIJKE PHILIPS N.V.**, Eindhoven (NL)

(**) Term: **15 Years**

(21) Appl. No.: **29/861,609**

(22) Filed: **Dec. 1, 2022**

(51) LOC (15) Cl. **13-03**

(52) U.S. Cl.

USPC **D13/182**; D18/56

(57) **CLAIM**

The ornamental design for a handle for nanoimprinting machine as shown.

DESCRIPTION

FIG. 1 is a perspective view showing a handle for nanoimprinting machine design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

1 Claim, 3 Drawing Sheets
